FOUNTAIN ATTACHMENT FOR FAUCETS

Joseph P. Brunetti, Clarksburg, W. Va.

Application January 14, 1938, Serial No. 185,050

1 Claim. (Cl. 299—9)

This invention relates to a fountain attachment for faucets, the general object of the invention being to provide a member for fitting over the discharge end of a faucet and having a passage therein through which the water passes from the faucet and said member having a smaller passage connecting the first passage with the upper portion of the member whereby when the flow of water from the faucet through the device exceeds 5 a certain amount some of the water will pass through the second passage and discharge therefrom in an upwardly directed stream so that one can drink from the stream. Thus one can drink some of the water flowing from the faucet without 10 using a glass or cup and without interfering with the ordinary uses of the faucet.

This invention also consists in certain other features of construction and in the combination and arrangement of the several parts to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is an elevation showing the invention applied to a faucet.

Figure 2 is a top plan view of the invention.

Figure 3 is a section on the line 3—3 of Figure 2. While the drawing shows the device formed of rubber or the like it is to be understood that the device can be formed of any suitable material.

As shown in this drawing the device includes 35 a body 1 having an enlargement 2 at one side thereof, preferably at the front thereof, and said body is formed with a passage or bore 3 passing from its top through its bottom, the upper portion of the passage or bore being enlarged to fit 40 over the discharge end 4 of the faucet A as shown in Figure 1 for vertical sliding movement thereon and also rotary movement for a purpose presently seen. The lower end of the passage or bore is smaller than the upper portion as shown at 4 45 and if desired non-splash screening 5 may be placed at the junction of the large part of the passage with the smaller part, said screening 5 limiting upward sliding of the body 1. An upwardly and outwardly sloping small passage 6 extends from the lower portion of the large part 50 of the main passage or bore through the enlarged part 2 and opens out through the top of this enlarged part. As will be manifest, by sliding the described device on the discharge end of the faucet 55 A into the described limit of its upward move-

ment the inlet end of the passage 6 may be closed by said end of the faucet and by sliding said device downwardly out of said limit said passage may be opened. Thus, when the faucet is open also the passage 6 the water will pass through the device, as shown at 7 in Figure 1 and if the faucet is only open partially the water will flow through the device and none of the water will escape through the passage 6. However, when the faucet is open to a greater extent the increased flow of water cannot all escape through the main passage or bore and then some of this water will pass through the passage 6 and discharge therefrom in an upwardly directed stream as shown at 8 in Figure 1 which will enable one 15 to drink from this stream. Of course, the height of this stream 8 will depend on the amount of water flowing from the faucet which, of course, is controlled by the amount of opening of the valve of the faucet.

Thus one can drink from the water passing from the faucet without using a glass, cup or the like and without touching the device and without getting his hands wet and thus the device makes it possible for one to readily secure a drink from 20 the faucet without danger of contaminating the water so that the device is absolutely sanitary. Also it is not necessary to remove the device when using the water from the faucet for ordinary uses as the device will not interfere with the passage 25 of water from the faucet to a sink or receptacle and by regulating the flow of water from the faucet by the hand operated valve the water can be made to discharge from the device without passing through the passage 6 or it can be made to 30 eject some of the water from said passage 6 in order to provide a stream from which the user 35 can drink from.

As will be seen from Figure 1 the device is so formed and the parts so arranged relative to the faucet that it will be practically impossible for one to place his mouth in contact with the device which adds to the sanitary nature of the device and the inclination of the passage 6 causes the stream 8 to be directed upwardly and forwardly 40 of the faucet so that one can drink from the stream without danger of his head coming in contact with any part of the faucet.

Whenever it is desired not to use the device as a fountain it may be used as an anti-splash device by so positioning the body on the faucet as to cause the inlet end of the passage 6 to be closed by a portion of the faucet with said portion engaging the screen. Then all the water from the faucet will pass through the screen, thus pro- 45 50 55

viding a non-splash attachment for the faucet. In this use of the device the same may be turned on the faucet A to locate the enlargement 2 rearwardly under the faucet A in an out-of-the-way position.

5 By placing a perforated plate under the screen the device will form washing or cleaning means for vegetables, dishes, etc.

Of course by positioning the body on the faucet 10 with the inlet of passage 6 below the faucet and using the screen and perforated plate, the device will form a combined fountain, non-splash device and washing and cleaning means. When the device is so used and water tends to pass through 15 the passage 6, the user can place his finger over the upper end of the passage 6 to stop the escape of water therefrom.

It is thought from the foregoing description that the advantages and novel features of the 20 invention will be readily apparent.

It is to be understood that changes may be made in the construction and in the combination and arrangement of the several parts provided that such changes fall within the scope of the 25 appended claim.

Having described the invention, what is claimed as new is:

A fountain attachment for faucets comprising a single piece sleeve of resilient material having a bore adapting the same for fitting rotatably over the discharge end of the faucet and upward and downward adjustment thereon, and an upwardly inclined spout portion extending from one side thereof and including a passage communicating at its lower end with said bore adjacent the lower end of the latter whereby said passage may be opened and closed by said faucet under 5 adjustment of said sleeve downwardly and upwardly to different positions, said sleeve having a partitioning screen in the bore thereof immediately below said lower end of the passage coacting with said faucet under upward adjustment 10 of the sleeve to establish the closing position of the latter, the bore below said screen being reduced in diameter to restrict the discharge of water from said sleeve whereby when the sleeve is adjusted to open the passage water above 15 said screen is caused to jet from said spout portion, said spout portion terminating flush with the upper end of the sleeve for location under the faucet in a rearwardly extending out-of-the-way position under rotation of the sleeve.
